UNITED STATES PATENT OFFICE

94,826

DESIGN FOR A SHIRT COLLAR

Sol F. Garfein, New York, N. Y.

Application July 5, 1934, Serial No. 52,465

Term of patent 14 years

To all whom it may concern:

Be it known that I, Sol F. Garfein, a citizen of the United States, residing at New York city, in the county of New York and State of New York, have invented a new, original, and ornamental Design for Shirt Collars, of which the following is a specification, reference being had to the accompanying drawing, forming a part thereof.

The figure is a perspective view of a shirt collar showing my new design.

The dominant feature of applicant's design consists in the arrangement of the back half of the collar substantially horizontal and straight, and the front half, of two quarter sections extending downwards from the ends of the back

half and at an angle substantially 90° from each other. The top edges of the two quarter sections are straight while the bottom edges are concaved. The adjacent edges of the two quarter sections have one third of their height, at the tops, diverging from each other at a small angle of approximately 5° , while the lower two thirds diverge at substantially 90° , in the 90° position of the two quarter sections.

I claim:

The ornamental design for a shirt collar, as shown and described.

In testimony whereof I have affixed my signature.

SOL F. GARFEIN.
